UNITED STATES PATENT OFFICE.

ELMYR A. LAUGHLIN, OF OREGON, ILLINOIS.

CAR BOLSTER.

1,407,551.

Specification of Letters Patent. Patented Feb. 21, 1922.

Application filed November 12, 1921. Serial No. 514,674.

To all whom it may concern:

Be it known that I, ELMYR A. LAUGHLIN, a citizen of the United States, and a resident of the city of Oregon, county of Ogle, 5 and State of Illinois, have invented certain new and useful Improvements in Car Bolsters, of which the following is a specification.

My invention relates to improvements in 10 car bolsters, especially adapted for use as a truck bolster of a railway truck, and has for its object the provision of a light, strong and durable construction of this character, which is highly efficient in use.

Another object of the invention is the 15 provision of such a bolster arranged and adapted to be readily cast in one integral piece.

Other objects will appear hereinafter. 20 The invention consists in combinations and arrangements of parts hereinafter described and claimed.

The invention will be best understood by 25 reference to the accompanying drawings, forming a part of this specification, and in which,

Fig. 1 is a top plan view, shown partially in horizontal section, of a truck bolster embodying the invention,

Fig. 2 is a longitudinal vertical section of 30 the same,

Fig. 3 is an end view of the same, and

Fig. 4 is a bottom plan view of the same.

The preferred form of construction, as 35 illustrated in the drawings, comprises a bolster member 5 made in channel form with its open side down and of substantially the same depth from end to end. The channel member 5 is provided centrally with a 40 center bearing comprising a vertical oblong sleeve 6 extending the full depth of the channel member 5, and having its sides joined to the sides of said channel member by means of transverse reinforcing webs 7,

45 as shown. Arranged on top of the channel member 5 is an annular oblong flange 8 surrounding the opening of sleeve 6 and reinforced by radiating webs 9 as indicated, and whereby a suitable center bearing for 50 the truck bolster is provided.

Arranged on top of the channel member 5, adjacent each end thereof, is a box-like side bearing member 10, adapted and arranged to contain any usual or desired form of 55 rocker side bearings for the car body. The outer wall of each of the side bearing mem-

bers 10 is reinforced by webs 11 and the inner wall 12 thereof is made hollow and provided with a comparatively wide flat top surface 13 adapted to constitute a slide bearing co-operating with the usual slide bearings on a car bolster, and whereby a very strong and rigid inner wall is provided. This inner wall is further reinforced by 60 means of stiffening webs 14, as shown. 65

Each end of the channel member 5 is further reinforced by means of a longitudinal centrally arranged reinforcing web 15 extending inwardly from each end of the channel substantially the full depth 70 thereof, and to a point under the corresponding side bearing member 10, the inner end of the web 15 being beveled upwardly at 15'. A transverse reinforcing web 16 is arranged substantially centrally under each 75 of the side bearing members 10 extending the full width and depth of the channel member 5, and joined with the web 15 and the sides of said channel member. A reinforcing bottom plate 17 extends inwardly 80 from each end of the channel 5 the full width thereof and joining at its inner end with the bottom of the corresponding transverse web 16. At each side of each end the channel member 5 is provided with 85 lateral lugs 18, forming guide members for engagement with the usual side frame of the car truck in the usual way.

As shown all parts of the bolster are 90 formed integral with each other and from a single steel casting, and whereby the economical production of the bolster is greatly facilitated. The construction disclosed is a strong, durable and highly efficient one for the purpose and very light in 95 weight, thus further facilitating economical production. The specific form and arrangement of the respective parts is a simple and efficient one for the purpose and permits of the ready casting of the bolster all in one 100 piece and at a single casting operation.

While I have illustrated and described the preferred form of construction for carrying my invention into effect, this is capable of variation and modification without departing 105 from the spirit of the invention. I, therefore, do not wish to be limited to the precise details of construction set forth, but desire to avail myself of such variations and modifications as come within the scope 110 of the appended claims.

Having described my invention, what I

claim as new and desire to secure by Letters Patent is:—

1. A bolster in channel form arranged with its open side down; side bearing members formed on the top of said channel adjacent to each end thereof; a longitudinal reinforcing web extending substantially centrally from each end of said channel inwardly substantially the full depth of said channel to a point beneath the corresponding side bearing member, the inner end thereof being beveled upwardly; a transverse reinforcing web arranged substantially centrally under each side bearing member extending across and substantially the full depth of said channel; and a bottom reinforcing plate extending from each end of said channel inwardly substantially the full width thereof and joining with the bottom of said web, substantially as described.
2. A bolster in channel form arranged with its open side down and of substantially uniform depth from end to end; a center bearing formed in said bolster consisting of a vertically arranged sleeve extending substantially the full depth of said channel; and transverse webs joining the sides of said sleeve with the sides of said channel, substantially as described.
3. A bolster in channel form arranged with its open side down; side bearing members formed on the top of said channel adjacent to each end thereof; a longitudinal reinforcing web extending substantially centrally from each end of said channel inwardly substantially the full depth of said channel to a point beneath the corresponding side bearing member, the inner end thereof being beveled upwardly; a transverse reinforcing web arranged substantially centrally under each side bearing member extending across substantially the full depth of said channel; a bottom reinforcing plate extending from each end of said channel inwardly substantially the full width thereof and joining with the bottom of said transverse reinforcing web; and a center bearing formed in said bolster consisting of a vertically arranged sleeve extending substantially the full depth of said channel and transverse webs joining the sides of said sleeve with the sides of said channel; and an oblong annular flange on top of said channel surrounding said sleeve, said flange being reinforced by radiating webs, substantially as described.
4. A bolster in channel form arranged with its open side down and of substantially uniform depth from end to end; side bearing members formed on the top of said channel adjacent each end thereof; said bearing members being substantially in box form and provided with an outer wall reinforced by stiffening webs and an inner hollow wall provided with an upper flat bearing surface and reinforced on the inner side by stiffening webs; a longitudinal reinforcing web extending substantially centrally from each end of said channel inwardly substantially the full depth of said channel to a point beneath the corresponding side bearing member, the inner end thereof being beveled upwardly; a transverse reinforcing web arranged substantially centrally under each side bearing member and extending across and substantially the full depth of said channel; a bottom reinforcing plate extending from each end of said channel inwardly substantially the full width thereof and joining with the bottom of said transverse reinforcing web; a center bearing formed in said bolster consisting of a vertically arranged oblong sleeve extending substantially the full depth of said channel and transverse webs joining the sides of said sleeve with the sides of said channel; and an oblong annular flange on top of said channel surrounding said sleeve, said flange being reinforced by radiating webs, substantially as described.

5. A bolster in channel form arranged with its open side down of substantially uniform depth from end to end; side bearing members formed on the top of said channel adjacent each end thereof; a longitudinal reinforcing web extending substantially centrally from each end of said channel inwardly substantially the full depth of said channel to a point beneath the corresponding side bearing member; and a transverse reinforcing web arranged substantially centrally under each side bearing member and extending across and substantially the full depth of said channel and joined with the corresponding longitudinal web and the sides of said channel, substantially as described.

In testimony whereof I have signed my name to this specification in the presence of two subscribing witnesses.

ELMYR A. LAUGHLIN.
